N. C. OVERCASH

BOBBIN SUPPORT FOR HAND KNITTING MACHINES

Filed July 24, 1924

By Watson E. Coleman
Attorney

UNITED STATES PATENT OFFICE.

NELLIE C. OVERCASH, OF SAWTELLE, CALIFORNIA.

BOBBIN SUPPORT FOR HAND KNITTING MACHINES.

Application filed July 24, 1924. Serial No. 727,993.

To all whom it may concern:

Be it known that I, NELLIE C. OVERCASH, a citizen of the United States, residing at Sawtelle, in the county of Los Angeles and 5 State of California, have invented certain new and useful Improvements in Bobbin Supports for Hand Knitting Machines, of which the following is a specification, reference being had to the accompanying 10 drawings.

This invention relates to knitting machines, and particularly relates to means for supporting a bobbin upon a hand knitting machine.

15 In hand knitting machines using the ordinary bobbin, when the thread is low the thread catches on the top of the bobbin and breaks, and when the bobbin is full the thread often catches on the weight or on 20 the thread guide and thus causes the thread to break and thus let the sock or stocking come off of the needles.

One of the objects of the present invention is to do away with this chance of breaking the thread by supporting a thread spool at such a distance from the knitting machine that the thread will not catch either upon the upper end of the original bobbin support or upon the thread guide or weight.

30 A further object is to provide a spool support which is so constructed that it may be attached by simply placing it upon the usual stand, the support under these circumstances supporting the knitter or machine, and being so constructed that when in place it will not move around or come off the stand, the support being so constructed, however, that it can be moved around with the machine without trouble.

40 A still further object is to provide an attachment for use with a knitting machine stand which will permit of the use of a thread spool as well as the usual bobbin on the machine which is used when reinforcing an article.

Another object is to provide a spool holder which will project out far enough and be sufficiently high as to make it easy to use the thread from the spool when using a reinforcing thread and thus have both threads very close to hand.

My invention is illustrated in the accompanying drawing, wherein:—

50 Figure 1 is a perspective view of a circular knitting machine and stand with my attachment applied thereto;

Figure 2 is a top plan view of the attachment;

Figure 3 is a top plan view of the ordinary 60 knitting machine stand;

Figure 4 is a section on the line 4—4 of Figure 3;

Referring to these drawings, it will be seen that I have illustrated a stand upon which a circular hand knitting machine is 65 mounted. This stand has a substantially circular flat rim 10 with a raised edge 11 extending partly around it. This stand is supported by three legs 12 connected at their lower ends by braces 13. The raised 70 edge 11 of member 10 is interrupted at the front of the stand, as at 14, and the rim is cut inward or recessed, as at 15. These raised edges 11 or flanges extend only partly around the rim 10. Projecting rearward 75 from the rim 10 is a rearwardly extending, U-shaped portion 16. On each side of this U-shaped portion there are relatively shallow needle trays 17. The rear wall 18 of the U-shaped portion 16 is relatively flat and 80 relatively wide.

So far I have described the ordinary knitting machine stand such as is commonly used. The knitting machine ordinarily used with such a stand as this may be of any 85 ordinary or conventional construction but is shown as having a circular body 19 which is disposed over the central opening in the supporting rim 10 and as resting upon this rim so that the stocking or sock or other 90 article being knitted passes downward through the center of the knitting machine and down through the central opening in the rim 10.

The knitting machine is provided with a 95 downwardly and rearwardly projecting clamping ear 20 and two outwardly projecting divergent ears 21 disposed on each side of the clamping ear. The clamping ear 20 is provided with a set screw whereby 100 the device may engage with the stand or with the table. Mounted upon one of the ears 20 is a spindle 22 adapted to carry the usual cone-shaped bobbin. The machine is also provided with the usual guide rod 23 105 upon which the weight 24 is mounted and with the thread guide 25 having eyes 26. When a hand knitting machine of this character is used, the thread coming from the bobbin 22^a on the bobbin support 22 is 110 very liable to catch on the top of the bobbin because the bobbin 22^a is disposed too

closely to the guide rod 25 and it leans outwardly and the thread passing through the eyes in the guide rod 25 and coming off of the bobbin catches on the upper extremity 5 of the bobbin. When the bobbin is full, the thread when unwinding catches on the little wire 27 which is on the weight 24.

My improvement, as before stated, contemplates the use of a spool support which will 10 support a spool in such position that the spool will not sit close to the guide rod 23, that the spool is not cone-shaped and, therefore, the thread will not catch on the top of the spool, and that the thread shall 15 come at such an angle as to prevent any possibility of the thread catching on the top of the usual bobbin 22^a. So far I have described the ordinary knitting machine stand such as quite commonly used and an ordinary 20 type of circular automatic hand operated knitter, it being understood that the knitting machine and the stand are neither of them parts of my invention but that they are standard articles and that any suitable 25 stand and any type of knitting machine of the general character illustrated are intended to be signified by the drawings.

My improved spool holder comprises a sheet metal plate 28 which is cut out in the 30 center so as to conform, generally speaking, to the shape of the rim 10 and rest thereon, the plate being further formed to provide a rearwardly projecting flat web 29 having somewhat divergent side edges. The central opening is extended into this web 29, as at 30. The frame formed by cutting out the plate 28 is so formed as to provide a relatively narrow portion 31 which coincides with the relatively narrow portion of the 35 rim 10 behind the recess 15, this narrow portion 31 resting upon this narrow portion of the rim 10.

The rear portion of the rim 28 is formed with radially projecting shoulders 32 which 40 engage behind the rear ends of the flanges 11, thus preventing the plate or rim 28 from oscillating upon the rim 10. The rear end of the web 29, which, as before stated, is made of sheet metal, is relatively wide and 45 preferably beaded, and a relatively heavy bail-like member 33 is supported within this bead having upwardly extending arms whose extremities are inwardly turned and 50 adapted to be disposed within openings formed in the extremities of the spool spindle 34.

In use, this improved spool holder is disposed upon the stand, the slot or extension 55 of the central opening being coincident with the opening in the U-shaped member 16 of the stand. The knitting machine is then disposed upon the rim 28. The medially disposed ear 19 extends downward through or is received by the openings 30 and 16. A set screw on the extremity of

this ear engages the flat portion or wall at the end of the opening 16 in the usual manner. The ears 20 extend over the laterally disposed flat walls of the opening 16 and, therefore, over the portion of the web 29 on each side of the opening 30. The thread is wound upon the spool 31 in an obvious manner.

Preferably this device is made of steel about $\frac{1}{16}$ " thick, the spool being about 3" 75 in diameter and about from 8" to 6" long. My attachment supports the spool spaced from the guide rod and inasmuch as the spool is not cone-shaped, the thread will not catch on the apex of the cone. The thread comes from such an angle as to prevent this. The attachment rests upon the stand and the machine seats on the attachment and on the stand with the clamp disposed downward through the opening 80 and clamping to both devices.

While I have illustrated this attachment as applied to a stand and while this attachment is particularly adapted for a stand, I wish it understood that it may be applied to a table in exactly the same manner and that here again it will support the spool in such spaced relation as will prevent the thread from the spool catching over the usual bobbin support or on the thread 90 guide or weight.

I claim:

1. As an article of manufacture, an auxiliary spool support for hand operated knitting machines comprising a sheet metal member cut out at one end to form a substantially annular portion adapted to be disposed beneath the knitting machine and engaged therewith against rotary movement, the annular member having a radial outstanding web carrying an auxiliary spool at its outer end, the opening of the annular member being extended outward into said web whereby to accommodate the usual clamps on a knitting machine.

2. As an article of manufacture, an auxiliary spool support of sheet metal formed to provide a somewhat narrow annular portion, the front of the annular portion being recessed, the rear of the annular portion on each side being widened to provide two outstanding shoulders whereby to receive and accommodate the flanges of the usual knitting machine support, the sheet metal being radially extended to form a web, the outer end of the web having upwardly extending arms to detachably support an auxiliary spool.

3. As an article of manufacture, an auxiliary spool support of sheet metal formed to provide a portion adapted to be disposed beneath a circular knitting machine and a portion extending rearward thereof, the first named portion having an opening, the rear of the opening being rearwardly extended,

the front portion of the opening having a transversely extending straight edge at an inclination to the longitudinal axis of the support and there being a recess extending inward from the periphery of the first named portion of the support toward said straight edge, the periphery of the support laterally of said recess being concentrically curved and formed to provide oppositely disposed, outwardly projecting shoulders whereby to receive and accommodate the flanges of the usual knitting machine support and rest thereon, the rearwardly extending portion of the support being in the form of a web having upstanding arms, 15 and a spool rotatably mounted upon said arms.

In testimony whereof I hereunto affix my signature.

NELLIE C. OVERCASH.
